CLOTHES HAMPER OR SIMILAR ARTICLE

Jon W. Hauser, St. Charles, Ill., assignor to Hawley Products Company, St. Charles, Ill., a corporation of Illinois

Application March 7, 1955, Serial No. 34,878

Term of patent 14 years

(Cl. D58—4)

FIG. 1

FIG. 2

FIG. 4

Fig. 1 is a front elevational view of a clothes hamper or similar article, embodying my new design;

Fig. 2 is a side elevational view thereof;

Fig. 3 is a top plan view thereof; and

Fig. 4 is a bottom plan view thereof.

I claim:

The ornamental design for a clothes hamper or similar article, as shown.
